WITNESS:

UNITED STATES PATENT OFFICE.

FRANK ROBERTSON, OF NEW ORLEANS, LOUISIANA, ASSIGNOR OF ONE-HALF TO
BENJAMIN HART, OF NEW ORLEANS, LOUISIANA.

LADDER.

Application filed August 19, 1922. Serial No. 582,918.

To all whom it may concern:

Be it known that I, FRANK ROBERTSON, a citizen of the United States, residing at New Orleans, in the parish of Orleans and State 5 of Louisiana, have invented new and useful Improvements in Ladders, of which the following is a specification.

This invention relates to extension ladders and has for an object the provision of 10 means whereby the height of a ladder may be easily and quickly regulated.

Another object of the invention is the provision of an extension step ladder, wherein both the step sections and the brace are 15 adjusted to regulate the height of the ladder platform, novel means being provided for holding the step sections and the brace sections in adjusted position.

With the above and other objects in view, 20 the invention further includes the following novel features and details of construction, to be hereinafter more fully described, illustrated in the accompanying drawings and pointed out in the appended claim.

25 In the drawings:—

Figure 1 is a front elevation of a ladder constructed in accordance with the invention.

Figure 2 is a rear elevation of the same.

30 Figure 3 is a side elevation.

Figure 4 is a horizontal section on the line 4—4 of Figure 3.

Figure 5 is an enlarged vertical section 35 through the ladder showing the means for holding the ladder sections extended.

Figure 6 is a similar view of the brace sections.

Referring in detail to the drawings, where-in like characters of reference denote corresponding parts, the invention as shown comprises step sections 10 and 11, each of which 40 include side rails 12 and rungs 13. The section 10 is secured to a platform 14, as shown at 15, while the section 11 is slidably mounted upon the section 10. For this purpose each of the side rails of each section 45 carries a substantially L-shaped arm 16, two of which are secured to the upper end of the side rails of one section, while two are secured to the lower ends of the side rails 50 of the other section. The arms 16 are located upon the outside of the side rails 12, while the inside of each of the side rails of the

section 11 has secured thereto an arm 17, which extends over and engages the inner 55 face of the side rail of the other step section.

The sections 10 and 11 are thus capable of relative sliding movement so as to permit the ladder to be adjusted and in order to hold 60 the latter in adjusted position, each of the side rails 12 of the step section 11 has pivotally secured thereto as shown at 18, one arm of a bracket 19. The outer end of this arm extends across the inner face 65 of the side rail of the other step section 10 and is formed to provide a seat 20 for the reception of the rungs 13 of the said step section 10. The opposite end of the bracket 19 is curved to provide a rung engaging seat 70 21, while at its extremity the bracket is provided with an eye 22. A connecting rod 23 engages the eyes 22 of each of the brackets 19 so as to provide an operating handle and to insure simultaneous pivotal movement 75 of the bracket, while a brace rod 24 serves as an additional means for connecting and bracing the brackets.

When the ladder is being extended, the 80 brackets 19 will engage the rungs of the step section 10 and will drop by gravity, their limit of downward movement being regulated by the engagement of the stops 21 with the rungs of the ladder section 11. As soon as the sections are extended the desired 85 length, a slight inward movement will cause the rungs of the step section 10 to engage the seats 20 of the brackets 19 so as to hold the sections against further collapsing movement. When fully collapsed, the sections are 90 held against accidental extension by means of hooks 25 which are carried by the section 10 and engage eyes 25' carried by the section 11.

The brace of the ladder is also of sectional 95 formation and includes an upper section 26 and a lower section 27, which are slidably connected together by means of substantially L-shaped arms 28 which are located upon the outside of the side rails 29 of the upper brace 100 section and arms 30 which are located upon the inside of said side rails, after the manner of the arms 16 and 17.

Pivots secured to the side rails of the brace section 27, as shown at 31 are yokes 105 32. These yokes include spaced substantially

parallel arms which are positioned upon opposite sides of the side rails 29 of the brace section 27 and are provided at one end with an eye 33 which is engaged by the opposite 5 ends of a combined connecting and operating rod 34, whereby the yokes may be simultaneously moved. The opposite ends of the arms of these yokes have positioned there-between a roller 35, which is adapted to drop 10 into spaced notches 36 provided in the side rails 29 of the brace section 26. These rollers will drop by gravity into the notches and will hold the brace sections in extended position.

15 The platform 14 is provided with a hook 37 which is adapted to engage the lower brace section 27 to hold the same in collapsed position.

20 The invention is susceptible of various changes in its form, proportions and minor details of construction and the right is herein reserved to make such changes as properly fall within the scope of the appended claim.

Having described the invention what is claimed is:—

An extension ladder embodying separate step sections including side rails and rungs connecting the side rails, means connecting the sections to permit relative sliding movement, substantially V-shaped brackets having one of their ends pivotally secured to the inner faces of said rails of one section, the opposite ends of the brackets being curved to engage over a rung of the last referred to section and terminating in 30 eyes, a horizontal handle having its ends engaged in the eyes, seat provided in each bracket adjacent the apex of the V for engagement beneath an adjacent rung of the other step section, the apices of the brackets 35 terminating in eyes, and a rod engaged in said eyes and having its ends arranged between the side bars of the adjacent step section.

In testimony whereof I affix my signature.
FRANK ROBERTSON.
